JULIO PINAL, OF BROOKLYN, NEW YORK.

FUEL-VAPORIZER.

1,333,573.

Specification of Letters Patent.

Patented Mar. 9, 1920.

Application filed March 11, 1918. Serial No. 221,689.

To all whom it may concern:

Be it known that I, JULIO PINAL, a citizen of Mexico, residing at Brooklyn, in the county of Kings and State of New York, have invented certain new and useful Improvements in Fuel-Vaporizers, of which the following is a full, clear, and exact description, such as will enable others skilled in the art to which it appertains to make 10 and use the same.

This invention relates to heaters, and with respect to its more specific features, to liquid fuel heaters and vaporizers adapted for use with, among other devices, internal combustion engines.

One of the objects of the invention is the provision of a practical device for extracting heat from the exhaust of an internal combustion engine and utilizing it in the engine so as to increase the efficiency of the engine by heating the fuel prior to explosion.

Another object of the invention is the provision of a practical and efficient liquid fuel vaporizing device which is simple in construction and easy to clean and repair.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, wherein similar reference characters refer to similar parts throughout the several views,

Figure 1 is a vertical central section of a vaporizer embodying the invention;

Fig. 2 is a transverse section;

Fig. 3 is an elevation, partly broken away, showing some of the internal structure of 45 the vaporizer;

Fig. 4 is a plan of Fig. 3 partly in section;

Fig. 5 is an elevation, partly sectional, of certain chambers or drums, employed in the vaporizer; and

Fig. 6 is a plan of Fig. 5.

Referring now more specifically to the drawings, the numeral 1 indicates a pipe through which liquid fuel, as gasoline, or even crude oil, is conducted from a suitable 55 supply thereof to the vaporizer or radiator on its passage to the engine. The liquid

fuel, having been heated in the vaporizer, passes to the manifold of the engine through the pipe 2.

The elements of the vaporizer are arranged to provide two independent conduits, one for the material to be heated, in the present embodiment, the liquid fuel, and one for the material to heat the vaporizer, in the present instance, for the exhaust gases 65 from the internal combustion engine. The numeral 3 indicates an outer tubular member or conduit, and the numeral 4 indicates an inner tubular member or conduit located inside of the outer tubular member and 70 transversely spaced from the outer member so as to provide an annular passageway or pathway 5 between the inner and outer tubular members through which pathway the fuel may flow by gravity. The outer tubular member is closed at one end, as at 6, and in the present embodiment the inner and outer members or conduits are so disposed as 75 to conduct the materials in the present instance, the fuel and exhaust gases, in generally vertical directions. As illustrated, the liquid fuel from the source of supply enters the vaporizer through a port 7 in the upper portion of the outer tubular member and travels downwardly between the walls 80 of the conduits 3 and 4. By terminating the inner end of the inner tubular member 4 short of the bottom 6, the inner end of the inner member 4 will be spaced from the bottom 6 and an end space 8 will be formed in 85 the vaporizer so that the fuel flowing down between the walls may enter this space and communicate with the passageway through the tubular member 4. The numerals 9, indicate legs which support the member 4 90 in this spaced relation. At this point it may be noted that as the fuel flows through the space 5 it will be heated and gasified or vaporized so that the resultant gas will acquire 95 some pressure, enabling it to rise through the tube 4, the passage through the tube 4 being, in the present instance, augmented by the suction of the engine, as will be understood. It is desirable that the fuel in the passageway 5 shall be gasified or vaporized 100 by the time it reaches the space 8, and to this end means are provided to cause the flow of the fuel material around the conduit and longitudinally thereof, in what may be termed a helical path. To this end there is 105 fixed to the outer wall of the inner tubular member 4 a helical rib 10 which operates as

a baffle to direct longitudinal movement adjacent thereto in the space 5 and directs the flow of material around the inner tube, the material gradually descending and eventually emerging into the space 8. Within the inner tube 4 are a series of chambers 11 and 12 through which the different materials flow, in the present embodiment the chambers 11, being adapted to receive the exhaust gases 5 from the engine, and the chambers 12, the vaporized or gasified fuel, and means are provided to confine the flow of these different materials to the different pathways or chambers outlined so that the different materials will not mingle with one another, but 10 on the contrary, the material flowing in one conduit and its appurtenances, such as the chamber 11, will be excluded from the other conduit and the chambers 12, and vice versa. 15 The chambers 11 and 12 are effectively provided by a plurality of drums 13 spaced apart longitudinally fitting in the inner tubular member 4 so as to cut off passageway through member 4 around the drums 13, 20 the interior of the drums being placed in communication with each other by means of conduits or pipes 14, preferably passing across the space between the successive drums, the conduit 14 between one pair of 25 drums being disposed out of longitudinal alignment with the conduit 14 between the next adjacent pair of drums. Preferably the relative disposition of these two conduits is diametrically of the tube 4 so that 30 the gases pass across one space 11 at one side of the axis of the tube and across the next adjacent space at the other side, or in a zigzag manner, as will be understood. The numeral 15 indicates a pipe or conduit connected with the exhaust pipe of the internal 35 combustion engine and leading into the vaporizer so as to conduct the exhaust gases, in the present instance, into the first chamber 11 whence the gases pass to the other chamber 11 by way of pipes 16, heating these 40 spaces and the surrounding parts during their passage. Eventually the exhaust gases enter the interior of the space 11 which is adjacent the closed end 6 of the outer tubular 45 member, and from this space they enter a third conduit member 17 which in the present instance extends through the centers of the drums to a point outside the vaporizer, at which point the exhaust may be finally 50 discharged into the atmosphere. The pipes 16 provide passageways across the drums 13 and out of communication with the spaces 12, these pipes being arranged alternately on opposite sides of the center of the drums, 55 or in a zigzag manner.

The vaporized fuel enters the spaces or drums 12 between successive chambers 11 by way of the conduits or pipes 14, passing through the respective chambers 11.

60 Within the drums 13 through which the

fuel vapor passes, cleaning material, such as steel wool, may be arranged to take up impurities in the gas, as illustrated. If desired, wire mesh screens 18 may be disposed in the ends of the pipes 14 to assist in cleaning the gas and lessen deposit of material in these tubes. 70

Inasmuch as the pathway of the liquid fuel is generally vertical, the plane of the rib 10 is preferably inclined upwardly to 75 the surface of the inner tubular member 4 so that the tendency of the liquid on the ribs will be to flow, as it were, across the rib toward the inner tubular member rather than toward the outer member 3. Inasmuch as 80 in the present embodiment the inner tubular member with the helical rib affixed thereto is removable from the outer tubular member, the outer edge of the rib may not make sufficiently close connection with the inner 85 face of the tubular member 3 at all points so as to prevent escape of liquid across said rib. By inclining the rib as described, any such tendency to escape is mitigated. The 90 numeral 19 indicates a pipe communicating with the chamber 8 and controlled by a valve 20. The numeral 21 indicates another valve controlled pipe at a lower level than the pipe 19. In the practical construction of the vaporizer the fuel drums 13 may 95 be coupled together at properly spaced intervals by means of the conduit tubes 14 which are removably attached thereto. Each drum 13 will have a central opening, as by the provision of the tubular walls 22, 100 and this assemblage of connected drums may be passed onto the tube 17, the tube 17 passing through the openings provided by the walls 22. In this wise the assemblage of 105 fuel drums will be supported by the lowermost exhaust drum 11' which is secured to the end of the tube 17, and the whole may be lowered into the outer tube 3. One of the fuel conduit tubes, as 23, will pass through the exhaust drum 11', and a nut 24 may be 110 employed to hold the parts in place. In this way the drum structure and its appurtenances may be removably mounted in the inner tubular member. The inner tubular member 4 is also removably mounted in the outer tubular member 3, in the present instance being threaded into a depending 115 flange of an upper head 25 which cooperates with a flange 26 on the outer member 3 and may be bolted thereto by the bolts and wing nuts 27 and 28. It will be observed that the lowermost space 11, is between the lowermost drum 13 and the bottom of the tube 4. This lowermost space 11 is occupied by a 120 drum 11', shown in section in Fig. 3 which serves to support the assemblage thereabove in the proper depth in the tube 4. By connecting this supporting drum to the central conduit 17, the assemblage may be readily 125 lowered into operative position as one. The 130

fuel conduit 23 passes through the bottom of the tube 4, and by applying nut 24 the assemblage of drums is held in the tube 4.

Thus by the above described construction 5 are accomplished, among others, the objects hereinbefore referred to.

The vaporizer is of such a construction as to utilize as much of the heat of the exhaust as possible in a relatively small apparatus adapted for automobiles. The zig-zag arrangement of certain of the conduits, together with the helical rib, and the relatively large chambers forming part of the 10 conduits for the respective materials, promote the efficient vaporizing and gasification 15 of the liquid fuel.

When coupled to an internal combustion engine the pipe 15 receives the exhaust from the engine, and the gases issue from the vaporizer through the pipe 17, after having parted with some of their heat. The pipe 1 is connected with the liquid fuel supply and may be provided with a hand valve to regulate the flow of fuel to the vaporizer. The 25 fuel gases issue from the vaporizer through the pipe 2, which may lead these gases to the air inlet of the cylinder of the engine at a point close to the port in the cylinder for the entry of air. Under such circumstances the gasified fuel from the vaporizer 30 may act as a substitute or in addition to the usual atomizing carburetor supplying the same air inlet. Should it be desired to employ the ordinary atomizing form of carburetor, as for instance when the vaporizer 35 is out of order or when liquid fuel accumulates in the vaporizer, a pipe may be attached to the pipes 19 or 21, and liquid fuel from the chamber 8 delivered to the usual carburetor.

As many changes could be made in the above construction and many apparently widely different embodiments of this invention could be made without departing from 45 the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of 55 the invention which, as a matter of language, might be said to fall therebetween.

Having described my invention, what I claim as new and desire to secure by Letters Patent is:—

1. A vaporizer comprising, in combination, two independent conduits, one for material to be heated, and one for the material to heat the vaporizer, each conduit comprising a series of chambers through which 60 the materials flow, respectively, the cham-

bers of one series alternating with those of the other, one conduit comprising a helical pathway around the other.

2. A vaporizer comprising, in combination, two independent conduits, one for material to be heated, and one for the material to heat the vaporizer, each conduit comprising a series of chambers through which the materials flow, respectively, the chambers of one series alternating with those of the other, one conduit comprising a helical pathway around the other and around said 70 series of chambers.

3. A vaporizer comprising, in combination, two independent conduits, one for material to be heated, and one for the material to heat the vaporizer, each conduit comprising a series of chambers through which the materials flow, respectively, the chambers of one series alternating with those of the other, one conduit comprising a helical 80 pathway around the other and around said series of chambers, said conduits being disposed to conduct the materials in generally 85 vertical directions.

4. A vaporizer comprising, in combination, an outer tubular member, an inner tubular member, a plurality of communicating drums in said inner member spaced from each other to provide chambers alternating 90 with the drums, conduits adapted to establish communication between the spaces between said drums, a conduit communicating with one of the chambers of said inner tubular member and leading to the exterior 95 of the vaporizer, and means providing a helical pathway for the flow of material between the inner and outer tubular members.

5. A vaporizer comprising, in combination, an outer tubular member, a tubular member within the outer member, transversely spaced and removable from said outer member, a plurality of communicating drums in said inner member spaced apart longitudinally of said member, conduits 100 passing through said drums adapted to establish communication between the spaces between said drums, and a conduit communicating with one of said spaces and passing through the drums to the exterior of the 105 vaporizer.

6. A vaporizer comprising, in combination, an outer tubular member, a tubular member within the outer member, transversely spaced and removable from said outer member, a plurality of communicating drums in said inner member spaced apart longitudinally of said member, conduits 120 passing through said drums adapted to establish communication between the spaces between said drums, a conduit communicating with one of said spaces and passing through the drums to the exterior of the 125 vaporizer, and a helical rib between the inner and outer tubular members adapted to 130

direct the flow of material around said inner tubular member.

7. A vaporizer comprising, in combination, an outer tubular member, a tubular member within the outer member, transversely spaced and removable from said outer member, a plurality of communicating removable drums in said inner member spaced apart longitudinally of said member, 10 conduits passing through said drums adapted to establish communication between the spaces between said drums, and a conduit communicating with one of said spaces and passing through the drums to the exterior of the vaporizer. 15

8. A vaporizer comprising, in combination, an outer tubular member closed at one end, a removable tubular member within and transversely spaced from the outer 20 tubular member, the inner end of said inner member being spaced from the closed end of said outer member providing an end space communicating with the space transversely between the members, a helical rib 25 in said transverse space the plane of said rib being inclined to the normal to the wall of inner tubular member, a plurality of removable drums in said inner tubular member, said drums being spaced apart longitudinally of said member, conduits connecting 30 the interior of adjacent drums across the spaces therebetween, said conduits being arranged zig-zag, other conduits extending through said drums and connecting the 35 spaces between the drums, said last mentioned conduits being arranged zig-zag, and a third conduit leading from the outside of the vaporizer through the centers of the drums and the spaces therebetween into 40 communication with the space adjacent the closed end of the outer tubular member.

9. A vaporizer comprising, in combination, a tubular member, and a series of drums disposed in said tubular member so 45 as to cut off passage through said member around said drums, and means adapted to establish communication between the drums.

10. A vaporizer comprising, in combination, a tubular member, and a series of 50 drums disposed in said tubular member so as to cut off passage through said member around said drums, means adapted to establish communication between the drums, and means adapted to establish communication 55 between the chambers between said drums independently of the communication between said drums.

11. A vaporizer comprising, in combination, a tubular member and a series of drums 60 disposed in said tubular member so as to cut off passage through said member around

said drums, means adapted to establish communication between the drums, and means adapted to establish communication between the chambers between said drums independently of the communication between said drums, said first mentioned means comprising tubes extending across the chambers intervening said drums, and said second mentioned means comprising tubes extending 70 across said drums. 65

12. A vaporizer comprising, in combination, a tubular member and a series of drums disposed in said tubular member so as to cut off passage through said member around 75 said drums, means adapted to establish communication between the drums, means adapted to establish communication between the chambers between said drums independently of the communication between said 80 drums, said first mentioned means comprising tubes extending across the chambers intervening said drums, said second mentioned means comprising tubes extending across said drums, and a pipe opening into 85 one of said chambers and passing through said drums to a point outside said tubular member. 90

13. A vaporizer comprising, in combination, a tubular member, and a series of 90 drums disposed in said tubular member so as to cut off passage through said member around said drums, means adapted to establish communication between the drums, an outer tube in which said tubular member is disposed and from which it is laterally spaced, and a helical rib on said inner member in said space, the plane of said rib being inclined to the normal to said tubular member. 95

14. A vaporizer comprising, in combination, an outer tubular member closed at one end, an inner tubular member removably supported within said outer member and spaced therefrom laterally and adjacent 105 said end, a plurality of communicating drums fitting said inner member and spaced apart longitudinally thereof, the inner one of said drums opening into said outer member adjacent the closed end of the latter, and a tube entering said inner member and opening into a space adjacent one of said drums, said drums having passageways therethrough to establish communication between the spaces intervening the 110 drums. 110

In testimony whereof I affix my signature, in the presence of two witnesses.

JULIO PINAL.
